Attorney

UNITED STATES PATENT OFFICE.

JOSEPH S. SCHOTT, OF BURLINGTON, IOWA.

DESIGN FOR A HAME ATTACHMENT.

SPECIFICATION forming part of Design No. 18,345, dated May 22, 1888.

Application filed April 16, 1888. Serial No. 270,875. Term of patent 7 years.

To all whom it may concern:

Be it known that I, JOSEPH S. SCHOTT, a citizen of the United States, residing at Burlington, in the county of Des Moines and State of Iowa, 5 have invented a certain new and original Design for Hame Attachments; and I do declare the following to be a full, clear, and exact description of the invention, such as will enable others skilled in the art to which it appertains to make and use the same.

This invention relates to a design for adjustable draft-eyes for wood hames, and will be fully understood from the following description and claim, when taken in connection with the accompanying drawings, in which—

Figure 1 is a perspective view of my newly-designed draft-eye, and Fig. 2 is a side elevation of the same.

Heretofore draft eyes have been made which 20 presented, when viewed in perspective, as in Fig. 1, an upwardly and rearwardly curved extension terminating in a fork or bifurcation. In these forked branches were provided perforations and a rod employed to connect the 25 said branches at their outer ends.

The leading feature of my design consists in

a laterally-curved branch having an elongated eye, the forward end of the loop having an annular transverse aperture.

Referring by letter to the said drawings, A 30 indicates the forward end of the draft-eye, which has lower rounded external walls and a central aperture of annular contour.

B indicates the rear branch of the said draft-eye, which curves laterally and rearwardly, being formed in a loop by a central elongated eye, C. 35

Having described my design, what I claim is—

The design for a hame attachment herein 40 shown and described, the same consisting of the draft-eye having one end terminating in a curved border with an annular aperture, and its opposite end curved laterally and terminating in an elongated eye or loop, as set forth. 45

In testimony whereof I affix my signature in presence of two witnesses.

JOS. S. SCHOTT.
